(57) **CLAIM**

The ornamental design for a rugby jumper leg glove, as shown and described.

DESCRIPTION

This is related to U.S. Utility patent application 11/800,356 and U.S. Utility patent application 11/899,529.

FIG. 1 is an upward looking perspective view of a rugby jumper leg glove, showing my new design;

FIG. 2 is a back view thereof;

FIG. 3 is a front view thereof;

FIG. 4 is a left view thereof;

FIG. 5 is a right view thereof;

FIG. 6 is a top view thereof;

FIG. 7 is a bottom view thereof; and,

FIG. 8 is a two-dimensional pattern view of the material thereof.

My rugby jumper leg glove is characterized as a first substantially frusto-conical section, where a second partial conical section is integrally folded over from said first section forming two pockets which are held open by the arch-shaped attachment on the back (as shown, for example, in FIG. 2) and the mirrored question-mark-shaped attachment on the front (as shown, for example, in FIG. 3).
